GOLF CLUB HEAD

Linus P. Vachon, 151 Warren St., Newton Center, Mass.

Filed June 8, 1961, Ser. No. 65,514

Term of patent 14 years

(Cl. D34—5)

Fig. 1.

Fig. 2.

Fig. 3.

Fig. 4.

Fig. 5.

The portion of the shaft shown in FIGS. 1 and 2 in broken lines is for illustrative purposes only.

The characteristic feature of my design resides in the curved base and raised ribs all as shown.

I claim:

The ornamental design for a golf club head and shown and described.
